UNITED STATES PATENT OFFICE.

EDWIN C. PALMER AND SUMNER G. RYDER, OF CLEVELAND, OHIO,
ASSIGNORS TO THE STANDARD TOOL COMPANY, OF SAME PLACE.

REVOLVING EMERY-WHEEL DRESSER.

SPECIFICATION forming part of Letters Patent No. 448,787, dated March 24, 1891.

Application filed August 11, 1890. Serial No. 361,653. (No model.)

To all whom it may concern:

Be it known that we, EDWIN C. PALMER and SUMNER G. RYDER, citizens of the United States, and residents of Cleveland, county of 5 Cuyahoga, State of Ohio, have invented certain new and useful Improvements in Emery-Wheel Dressers, of which we hereby declare the following to be a full, clear, and exact description, such as will enable others skilled in 10 the art to which it appertains to make and use the same.

Our invention relates to improvements in revolving emery-wheel dressers, and it is designed to be equally adapted to operate upon 15 smaller sizes of emery-wheels as well as upon larger wheels. Its object is also to produce a more solid, immovable, and resisting foundation to wear than has hitherto been in use, and to present a constant cutting-edge to the 20 wheel to be operated upon.

Our invention consists in a revolving cylinder of hardened metal—such as cast-steel—mounted upon a suitable spindle-bearing and provided with radially-driven cavities on its 25 periphery arranged in close proximity in such a manner as to leave thin intervening edges between the cavities, and in the details of construction and manner of arrangement of the various parts, as shown in the drawings, 30 described in the specification, and more particularly pointed out in the claims.

In the accompanying drawings, Figure 1 is a perspective view of our improved cutter. Fig. 2 is a vertical cross-section of a tool 35 through the spindle-bearing. Fig. 3 is a perspective view of the cylinder detached, with a diagonal section cut through x x , Fig. 1. Figs. 4 and 5 are surface elevations of cutter-cylinder, showing cross-cuts on their peripheries.

A in the drawings shows a forked handle, provided with spindle-bearings a a' , between which is mounted the cutting-cylinder B upon the spindle C. This spindle C is secured 45 within the bearings a and a' by the set-screw a^2 .

Heretofore difficulty has been experienced in obtaining substantial cutters for this purpose, since many have been made in detached 50 sections or disks strung upon a spindle, which

are constantly passing one another in motion, and a varying surface is presented to the wheel, no permanent cavities being obtained. In our invention greater solidity is obtained with continuous sharpness of edge, and in 55 one direction, as shown in section diagonally, as in Fig. 3, the walls are seen to be perfectly straight from tip to base, thus wearing down evenly until worn to the hub. The thicker portions connecting these membranes 60 serve to support the parts and solidify the cutter. If drilled with a straight drill, there will be a slight taper of the walls, but not enough to interfere with usefulness; but, preferably, the drill-holes are reamed out 65 with a taper reamer. One of the chief advantages of our invention is the fact that a number of tools can be cut from one cylindrical rod of steel or chilled iron. The separate sections are then centrally bored to 70 receive the spindle, and the holes in the periphery can be drilled quickly and a number of them simultaneously. They are then ready to mount upon spindles. Deep-seated grooves, as D, may be sawed in different directions 75 about the periphery to aid in breaking up the surface.

What we claim, therefore, as new, and desire to secure by Letters Patent, is—

1. In an emery-wheel dresser, a solid cylindrical cutter bored longitudinally to receive a central spindle and from the periphery radially toward the hub to form cutting-edges, substantially as described.

2. In an emery-wheel dresser, a solid cylindrical cutter in one piece bored longitudinally to receive a central spindle and radially from the periphery to the hub to form cutting-edges, said radial borings being arranged regularly and in close juxtaposition to form 85 separating membranes b of unvarying thickness from edge to base, substantially as described.

3. A solid cylindrical cutter provided with a central longitudinal spindle-bearing, radial 95 borings extending from the periphery toward the center, but leaving a thickened portion for a hub, thick and thin membranes separating the cavities, the thin membranes having substantially parallel sides, and a suitable 100

spindle for the same, substantially as described.

4. A solid cylindrical cutter for dressing emery-wheels centrally and longitudinally bored to receive a spindle, and provided with radial and permanent cavities extending from the periphery toward the central cavity, sufficient space being left integral to form a hub,

in combination with deep-seated slots upon the periphery, substantially as described.

EDWIN C. PALMER.
SUMNER G. RYDER.
